UNITED STATES PATENT OFFICE.

STEPHEN D. FIELD, OF NEW YORK, N. Y.

ELECTRIC ELEVATOR.

SPECIFICATION forming part of Letters Patent No. 275,179, dated April 3, 1883.

Application filed November 16, 1882. (No model.)

To all whom it may concern:

Be it known that I, STEPHEN D. FIELD, a citizen of the United States, and a resident of the city, county, and State of New York, have invented certain new and useful Improvements in Electric Elevators, of which the following is a specification.

My invention relates to a method of and apparatus for raising and lowering elevator-cars by means of an electro-dynamic motor, and of controlling and regulating the action of the latter from a point within the car.

The accompanying drawing is a sectional view of an elevator-shaft, with its movable car and electromotor for operating the same, the circuit-connections being shown in diagram.

In the drawing, A represents the elevator-car, which is of the usual construction, and is movable up and down within a vertical inclosing-shaft, B, being suspended from above by one or more flexible ropes, C, attached to the top of the car and passing over pulleys c c at the top of the shaft. The opposite end of the rope or ropes C is attached to a winding-drum, D, mounted upon the axis of a toothed wheel, d, which in turn engages with a pinion upon the axis f of the rotating armature of an electromotor, F. This electromotor may be of any well-known or suitable construction, and may be placed in the basement of the structure containing the elevator, or upon any of the upper floors, the particular location in this respect being wholly immaterial. I have preferred to illustrate it in the present instance as being placed in the basement.

E represents an electric generator of any suitable character, preferably a dynamo-electric machine, which may be located at any convenient point either within or without the building in which the elevator is situated, and may even be situated at a considerable distance therefrom, an electric connection being established between the two by wires or conductors w and w', extending from the generator E to the point where the motor F is situated. The terminals 1 and 2 of the motor are preferably in permanent connection with the wires w and w', leading respectively from the positive and negative poles of the generator E.

G is a circuit-changer, which is pivoted at g to a stationary support in any convenient position, and provided with a metallic contact-arm, g', which latter is movable over a series of metallic contacts, i', i², and i³, these being disposed with reference to each other that when the arm g' passes from one of them to another an electric circuit will be closed through the second before contact with the first is interrupted, and vice versa. The circuit-changer G is also provided with two lever-arms, h' h', to which are attached the respective ends h h of a controlling-rope, H'. This passes from the arm h' over a pulley, h³, and vertically upward, passing through the interior of the movable car A, thence over a pulley, h⁴, at the top of the shaft B, returning vertically through the shaft, preferably outside the car A, and over a pulley similar to h³ to the opposite arm of the lever h'. A train of multiplying-gearing, D', engages with the toothed wheel d on the axis of the drum D, and terminates in a small but rapidly-moving drum, d'. When the apparatus is at rest the drum D' is held in check by the friction of a brake, H, which is mounted on the end of a lever, h², projecting from the circuit-changer G.

The terminals 1 and 2 of the electromotor F are, when the apparatus is in its normal position of rest, united by a shunt-conductor, s s', extending from the terminal 1 to the circuit-changer G, thence through the arm g', contact i', and conductor s' to the point 2. The second contact, i², is united with the terminal 2 of the motor F by a conductor, r r, in which is included an adjustable rheostat or artificial resistance, R, of any well-known or suitable construction.

The operation of the apparatus is as follows: Assuming the machinery to be in its normal position of rest, a constant current of electricity from the generator E passes over the wire w to the terminal 1 of the electromotor F, and thence over the shunt-conductor s, circuit-changer g', and conductor s' to the terminal 2, and thence by the conductor w' to the positive pole of the generator. Inasmuch as the resistance of the shunt-conductor s s' between the points 1 and 2 is inappreciable, no appreciable current passes through the electromotor F.

from the point 1 to the point 2. The tendency of the car A is therefore to descend by the action of gravity, and thereby to turn the motor F in a reverse direction; but this tendency is checked by the action of the friction-brake H upon the drum d', so that the apparatus remains immovable. When a person entering the car A desires to cause the same to ascend, he grasps the controlling-rope h and 5 pulls the same downward, which movement acts upon the arms h' h' of the circuit-changer G and shifts it to the position indicated by the dotted lines. In this position the shunt-circuit s s' is interrupted, and the full power of 10 the electric current from the generator E is at once exerted upon the electromotor F, causing the same to revolve rapidly in the direction indicated by the arrow, thus winding the rope C upon the drum D, and accordingly raising 15 the elevator-car toward the top of the shaft in the usual manner. The car may be stopped by the person riding within it at any desired point by reversing the operation last described and restoring the parts to the position shown 20 in the drawing, in which case the electric current is shunted around and withdrawn from the motor F, while the brake H is simultaneously applied to the drum d', thus holding the motor in check. When, on the other hand, it 25 is desired to cause the car to descend, the arm g' of the circuit-changer is placed upon the intermediate contact, i², by a proper manipulation of the controlling-rope h. In this position of the circuit-changer G the brake H is removed 30 from the drum d', while the shunt, which spans the electromotor F, is completed through the conductors s and r, thus including the adjustable artificial resistance R. Under these 35 circumstances the descent of the car by gravity will rotate the electromotor F in a reverse direction, thus in effect converting it into a dynamo-electric generator, the poles of which are connected by a shunt.

If the shunt is of very small electrical resistance, the mechanical resistance offered by the motor will, as is well known, be very considerable, and hence the car must necessarily descend very slowly; but by increasing the resistance of the rheostat R the descent 40 will become more rapid. The rheostat R should therefore be so adjusted that the descent of the car will be effected at a desirable and convenient rate of speed, according to the circumstances of the particular case. By 45 shifting the circuit-changer G so as to bring the brake H in contact with the drum d' the descent may be arrested at any desired point, as hereinbefore explained.

Two or more shunts of different resistances 50 may be employed in place of the shunt r r', each having its independent plate for making contact with the arm g'.

I claim as my invention—

1. The combination, substantially as hereinbefore set forth, of an electric generator, an

elevator-car, an electromotor actuated by a current from said generator for propelling said car against the action of gravity, and a circuit-changer for diverting the current of the generator away from the motor and simultaneously closing a shunt uniting the terminals of said motor for retarding its reverse movement. 70

2. The combination, substantially as hereinbefore set forth, of an electric generator, an elevator-car, an electromotor actuated by a current from said generator for propelling said car against the action of gravity, a circuit-changer for diverting the current of the generator away from the motor and simultaneously closing a shunt uniting the terminals of said motor for the purpose of retarding its reverse movement, and means for actuating said circuit-changer from a point within the movable car. 80

3. The combination, substantially as hereinbefore set forth, of an electric generator, an elevator-car, an electromotor actuated by a current from said generator for propelling said car against the action of gravity, a shunt spanning said electromotor for retarding its reverse motion under the action of gravity, and a switch or circuit-changer for opening and closing said shunt. 90

4. The combination, substantially as hereinbefore set forth, of an electric generator, an elevator-car, an electromotor actuated by a current from said generator for propelling said car against the action of gravity, a shunt spanning said electromotor for retarding its reverse motion under the action of gravity, a switch or circuit-changer for opening and closing said shunt, and an artificial resistance included in said shunt. 95

5. The combination, substantially as hereinbefore set forth, of an electric generator, an elevator-car, an electromotor actuated by a current from said generator for propelling said car against the action of gravity, a shunt spanning said electromotor for retarding its reverse motion under the action of gravity, a switch or circuit-changer for opening and closing said shunt, and an adjustable or variable artificial resistance included in said shunt. 105

6. The combination, substantially as hereinbefore set forth, of an electric generator, an elevator-car, an electromotor actuated by a current from said generator for propelling said car against the action of gravity, a shunt spanning said electromotor for retarding its reverse motion under the action of gravity, a circuit-changer or switch for opening and closing said shunt, and a friction-brake or stop for arresting the motion of the motor. 115

7. The combination, substantially as hereinbefore set forth, of an electric generator, an elevator-car, an electromotor actuated by a current from said generator for propelling said car against the action of gravity, a shunt 120

spanning said electromotor for retarding its reverse motion under the action of gravity, a circuit-changer or switch for opening or closing said shunt, a friction brake or stop for arresting the motion of the motor, and means for actuating said circuit-changer and brake from a point within the car.

In testimony whereof I have hereunto subscribed my name this 15th day of November, A. D. 1882.

STEPHEN D. FIELD.
